No. 36,862.

Patented March 29, 1904.

UNITED STATES PATENT OFFICE.

WILSON BROOKS, OF CHICAGO, ILLINOIS.

DESIGN FOR A GRAVE MARKER OR HEAD-PIECE.

SPECIFICATION forming part of Design No. 36,862, dated March 29, 1904.

Application filed January 28, 1904. Serial No. 191,063. Term of patent 14 years.

To all whom it may concern:

Be it known that I, WILSON BROOKS, a citizen of the United States, residing at Chicago, in the county of Cook and State of Illinois, 5 have invented a new, original, and ornamental Design for a Grave Marker or Head-Piece, of which the following is a specification.

The accompanying drawing shows an elevation of the design of the grave marker or head-piece.

What I claim, and desire to secure by Letters Patent, is—

The ornamental design for a grave marker or head-piece as shown.

WILSON BROOKS.
